(57) **CLAIM**

The ornamental design for a sound bug reproducing device, as shown and described herein.

DESCRIPTION

FIG. 1 is a top orthogonal view of the sound bug reproducing device of FIG. 1;

FIG. 2 is a left side orthogonal view of the sound bug reproducing device of FIG. 1;

FIG. 3 is a first orthogonal end view of the sound bug reproducing device of FIG. 1;

FIG. 4 is a second orthogonal end view of the sound bug reproducing device of FIG. 1; and,

FIG. 5 is a bottom orthogonal view of the sound bug reproducing device of FIG. 1.
